UNITED STATES PATENT OFFICE.

MORRIS BERKOWITZ, OF BROOKLYN, NEW YORK, ASSIGNOR TO EXCELITE FIXTURE CORPORATION, OF NEW YORK, N. Y., A CORPORATION OF NEW YORK.

DESIGN FOR A COMBINED CIRCULAR LIGHTING-FIXTURE PART AND SUPPORTING MEMBER FOR THE SAME.

Application filed July 17, 1924. Serial No. 10,177. Term of patent 3½ years.

To all whom it may concern:

Be it known that I, MORRIS BERKOWITZ, a citizen of the United States, residing in the borough of Brooklyn, Kings County, city and State of New York, have invented a new, original, and ornamental Design for a Combined Circular Lighting-Fixture Part and Supporting Member for the Same, of which the following is a specification, reference being had to the accompanying drawing, forming a part thereof.

The single figure of the drawing is a side elevation of a combined circular lighting fixture part and supporting member for the same showing my new design.

I claim:

The ornamental design for a combined circular lighting fixture part and supporting member for the same, as shown.

MORRIS BERKOWITZ.
